UNITED STATES PATENT OFFICE.

MINNIE GOLDSTEIN, OF SAN FRANCISCO, CALIFORNIA.

DESIGN FOR A GAME-BOARD.

SPECIFICATION forming part of Design No. 29,005, dated July 5, 1898.

Application filed April 7, 1898. Serial No. 676,827. Term of patent 3½ years.

To all whom it may concern:

Be it known that I, MINNIE GOLDSTEIN, a citizen of the United States, residing at San Francisco, in the county of San Francisco and State of California, have invented and produced a new and original Design for a Game-Board, of which the following is a specification, reference being had to the accompanying drawings, forming part thereof.

10 Figure 1 is a plan view of the game-board, and Fig. 2 is a longitudinal section of the same.

The game-board is made in the form of a box, having two sections 1 2 joined in the middle, as at 3, the sides 4 5 of the box being uniformly tapering. The top of each section of the box is formed with two parallel slots 6, each slot having at regular intervals notches

7. At the outer margins of said top sections are imprinted series 8 of representations of ordinary playing-cards—that is to say, there are the representations of various groups of hearts, spades, diamonds, and clubs, and of kings, queens, and knaves.

The leading or material features of my design are the tapering sides 4 5, the slots 6, having notches 7, and the representations 8 of ordinary playing-cards.

I claim—

15 The design for a game-board, substantially as shown and described.

MINNIE GOLDSTEIN.
